UNITED STATES PATENT OFFICE.

JOSEPH P. MARTER, OF CRAMER'S HILL, NEW JERSEY.

DESIGN FOR A STAND FOR OIL-CANS.

SPECIFICATION forming part of Design No. 27,145, dated June 1, 1897.

Application filed February 27, 1897. Serial No. 625,424. Term of patent 31 years.

To all whom it may concern:

Be it known that I, JOSEPH P. MARTER, a citizen of the United States, residing at Cramer's Hill, in the county of Camden and State of New Jersey, have invented and produced a new and useful Design for an Oil-Can Stand; and I do declare the following to be a full, clear, and exact description of the same, reference being had to the accompanying perspective drawing, forming a part thereof.

The invention relates to a stand for a swinging oil-can.

It consists of parallel feet or bottoms A, which are rounded at their ends *a* and recessed or inlet at their lower sides *b*.

B is a connecting-brace between the feet, which is widened at its ends *c* and joined with its reduced center *d* by reverse curving *e*.

D are conical parallel sides or housings fixed vertically to the feet A, each being provided with alined journal-openings E.

I claim—

The design for an oil-can stand, substantially as herein shown and described.

In testimony whereof I affix my signature in presence of two witnesses.

JOSEPH P. MARTER.

Witnesses:

FRANCIS D. PASTORIUS,
B. D. ARCHER.
